United States Patent Office.

ALFRED M. WEEKES, OF NEW YORK, N. Y.

Letters Patent No. 79,039, dated June 16, 1868.

IMPROVEMENT IN LAMP-SHADE.

The Schedule referred to in these Letters Patent and making part of the same.

TO ALL WHOM IT MAY CONCERN:

Be it known that I, ALFRED M. WEEKES, of the city, county, and State of New York, have invented a new and improved Lamp-Shade; and I do hereby declare that the following is a full, clear, and exact description thereof, which will enable those skilled in the art to make and use the same, reference being had to the accompanying drawings, forming part of this specification, in which—

Figure 1 represents a side view of my improved lamp-shade.

Figure 2 is a sectional elevation of the same.

Similar letters of reference indicate corresponding parts.

A is the shade, B the burner, and C the lamp-chimney.

In fig. 2, it will be noticed that the flame is wholly surrounded by the shade, but that the upper end of the flame is nearly on a level with the upper edge of the shade.

The demi-light produced above the flame is thus free to illuminate the room, while the main light will be reflected downward upon the table on which the lamp stands.

My invention consists in the application of one or more elongated projections, *a a*, which are formed on the lower edge of the shade, as shown, so that the same can be turned, to bring the projection between the light and a sick or weak person, while the rest of the shade will serve as a reflector.

These projections may be of suitable shape and size.

On the ring D are formed two or more upward-projecting arms or lugs, *b b*, which, when the shade has been fitted over and around the ring, can be bent over the upper edge of the shade, to clamp the same, as is clearly shown in the drawing.

The use of an outer ring is thus dispensed with, and the shade is fastened in a very simple manner to the inner ring.

I claim as new, and desire to secure by Letters Patent—

Providing the lamp-shade with one or more elongated projections, *a a*, substantially as and for the purpose herein shown and described.

ALFRED M. WEEKES.
